 York, N. Y., a corporation of New York

Application November 18, 1936, Serial No. 111,382

6 Claims. (Cl. 287—20)

This invention relates to devices for attaching members, and more particularly to a device for locking tubular flyer arms to driving heads of strand twisting machines of the general type disclosed in the H. H. C. Grondahl Patent 1,263,405 of April 23, 1918.

Objects of this invention are to provide an efficient and practical device for attaching to its support a tubular machine element subjected to great centrifugal stresses during motion.

In accordance with the above objects, the invention in one embodiment thereof as applied to the attaching of tubular flyer arms to driving heads of strand twisting machines of the aforementioned type, contemplates a device wherein a supporting bracket fixed to the driving head is formed with a recess to receive half the cross section of the tubular arm and a clamping plate also recessed to receive the other half of the arm are provided with aligned similar channels in their opposed recessed faces extending at right angles to and intersecting the recesses. Entered in the end of the arm is a hollow block having diametrically opposed grooves or peripheral channels aligned with the channels in the bracket and clamping plate, the aligned channels receiving locking pins. In locking the parts, the hollow block is fitted in the end of the tubular arm which is then laid in the bracket recess with a locking pin in its channel. Thereafter the recessed clamping plate with a locking pin in its channel is laid over the arm and fastening screws are driven home which serve to deflect opposite wall portions of the tubular arm into the channels of the block by the interposed locking pins, thus securely locking the arm to its supporting bracket and plate.

Other objects and advantages of this invention will more fully appear from the following detailed description, taken in connection with the accompanying drawing, wherein

Fig. 1 is a central vertical section of an attaching device embodying the features of this invention, the parts being shown in locked relation;

Fig. 2 is a similar view showing the parts in position ready to be locked together;

Fig. 3 is a fragmentary sectional view taken on the line 3—3 of Fig. 1, and

Fig. 4 is a fragmentary elevational view of Fig. 1 looking toward the right and downwardly on a line perpendicular to the face of the bracket.

In the drawing the invention is shown as applicable to a strand twisting machine such as is used in the manufacture of telephone cable. Since the twisting machine is of a well-known type, such as

is disclosed in the above referred to patent, and forms no part of this invention, only such parts thereof are illustrated which are necessary to a full understanding of the present application of the invention. Referring to the drawing, a rotatable bracket or driving head is indicated at 10, which carries a plurality of tubular yoke or flyer arms 11, the head and arms being shown fragmentarily. Since the driving head 10 and the flyer arms 11 carried thereby are rotated at a high rate of speed in the operation of strand twisting, the arms will consequently be subjected to great centrifugal stresses tending to pull away from their points of support on the driving head. The flyer arms 11, only one of which is shown, are securely locked to the driving head 10 by an attaching device comprising a split bracket, indicated at 12 and 13, the part 13 acting as a clamping plate in the final locking of the elements together. Each bracket part is provided with a recess 14 for receiving half the cross section of the tubular flyer arm 11, which in the present instance, as shown in Figs. 3 and 4, is larger in cross section in one direction than the other. The bracket part 12 is formed with an arm which is attached to the head 10 by screws 17 and the clamping plate 13 is secured to the part 12 by screws 18.

Within the end of the tubular flyer arm 11, which is locked to the bracket part 12, is fitted a hollow block or plug 19 having a slight taper from its upper end to its lower end, as viewed in Figs. 1, 2 and 4, the lower end having a snug fit in the arm, and the upper end is only enough larger that it will have a tight fit when driven into the tubular member. Preferably the lower end of the block 19 is bifurcated as shown (Fig. 4). The member 19 is provided with a strand passage 20 suitably shaped throughout its length to permit the twisted strands to pass therethrough without deleterious friction. Formed in the block 19 are diametrically opposed peripheral channels or grooves 21, of arcuate shaped contour, which extend transversely thereof, and at right angles to the bracket recesses 14. The bracket parts 12 and 13 are provided upon their inner faces with channels 24 of circular contour and aligned with the channels 21 of the block 19, the channels 24 intersecting the recesses 14 of the bracket parts. The channels provide open grooves in the recesses and terminate in drilled holes extending to the exterior of the bracket parts 12 and 13. Tightly fitted in each of the channels 24 is a locking key or pin 25 which projects for substantially one-half of its length and cross-sectional area into

the recess 14, as clearly shown in Figs. 1 and 2, due to the channel 24 intersecting the recess 14. Referring to Fig. 2, it will be apparent that upon the clamping plate 13 of the bracket being drawn 5 into position against the bracket part 12 by tightening the screws 18 that the locking pins 25 will deflect inwardly opposite portions 26 of the wall of the tubular flyer arm 11, the deflected portions being pressed into the channels 21 of the 10 block 19 which serves as a die or anvil to shape the wall portions about the locking pins.

To lock the tubular flyer arm 11 to the split bracket, the hollow tapered block 19 may be first fitted in the end of the arm with the channels 21 15 predeterminedly positioned relative thereto and the arm is then positioned in the recess 14 of the bracket part 12 (Fig. 2), the channel 24 thereof being aligned with the channel 21 of the block 19 which carries a locking pin 25. The recessed 20 clamping plate 13 carrying a locking pin 25 in its channel 24 is then laid over the arm 11 and the fastening screws 18 are driven home. As the screws 18 are threaded into the bracket part 12 the locking pins 25 are pressed against the opposite wall portions 26 of the arm 11 which portions are deformed and deflected into the channels 21 of the block 19 and when fully deflected, as shown in Fig. 1, serve to securely lock the arm 11 to its supporting split bracket. It will 25 be obvious in the particular application of the invention that the deflected wall portions 26 of the arm 11 which are locked to the split bracket and extend at right angles to the direction of the clamping action of the plate 13, which clamps 30 the arm between the bracket parts 12 and 13, will provide a maximum resistance to centrifugal 35 stresses set up tending to pull the arm away from the bracket.

Although the invention herein described and 40 illustrated is particularly well adapted for use in strand twisting machines, it will be understood that the invention is capable of many other modifications and applications and is to be limited only by the scope of the appended claims.

45 What is claimed is:

1. A device for attaching a tube to supporting members, comprising means having spaced peripheral transverse channels fitted within the tube, the members having recesses cooperating to receive the tube therein and transverse channels 50 intersecting the recesses and aligned with the channels in said means, the channels in the members having locking means entered therein abutting the periphery of the tube, and means for clamping the members together to cause said locking means to deform the wall of the tube into the channels of said means to firmly attach the tube to the members.

60 2. A device for attaching a tube to supporting members, comprising means having diametrically opposite peripheral transverse channels fitted within the tube, the members having recesses 65 cooperating to receive the tube therein and transverse channels intersecting the recesses and aligned with the channels in said means, the

channels in the members having locking pins entered therein and abutting the periphery of the tube, and means for clamping the members together to cause said locking pins to deform the wall of the tube into the channels of said means to firmly attach the tube to the members. 5

3. A device for locking a tube to a two part support, comprising a hollow plug having spaced peripheral transverse channels fitted in the tube, the support parts having recesses cooperating 10 to receive the tube therein and transverse channels intersecting the recesses and aligned with the channels in said plug, locking pins in the channels in the support parts, said pins abutting the periphery of the tube, and means for clamping the support parts together to cause said locking pins to deflect the wall of the tube into the channels of said plug to firmly lock the tube to the support. 15

4. A device for locking flyer arms of oblong 20 tubular cross-section to a driving two part support, comprising a hollow wedge fitting the inner periphery of the tubular flyer arm, said wedge having diametrically opposed transverse channels formed in its longer outer peripheral sides, 25 the support parts having recesses cooperating to receive the flyer arm therein and transverse channels intersecting the recesses and aligned with the channels in said wedge, locking pins fitted in the channels of the support parts and 30 abutting the periphery of the flyer arm, and means for drawing and retaining the support parts together to cause said locking pins to deflect the wall of the tubular flyer arm into the channels of said wedge to firmly lock the tubular 35 flyer arm to the driving support.

5. A device for attaching a hollow member to supporting members, comprising means having a transverse channel fitted within the hollow member, the supporting members having recesses 40 cooperating to receive the hollow member therein, one of the supporting members having a transverse channel intersecting the recess thereof opposite the channel in said means, the channel in the supporting member having locking means 45 entered therein, and means for clamping the supporting members together to cause said locking means to deform the wall of the hollow member into the channel of said means fitted in the hollow member to firmly attach the latter member 50 to the supporting members.

6. A device for locking a hollow member to a two part support, comprising a plug having a transverse channel fitted within the member, the support parts having recesses 55 cooperating to receive the member therein, one of the support parts having a transverse channel intersecting the recess thereof opposite the channel in said plug, a locking pin in the channel of the support part, and means for clamping the support parts together to cause said pin to deflect 60 the wall of the member into the channel of said plug to firmly lock the member to the support.
